AWNNG

George H. Foerster, Landover, Md., assignor to
The Automatic Awning Mfg. Co., Washington,
D. C.

Application May 19, 1932. Serial No. 612,335

2 Claims. (Cl. 156—15)

This invention appertains to new and useful improvements in window awnings and more particularly to an improved awning of the swingable type.

- 5 The principal object of the invention is to provide an awning in combination with a window sash whereby the awning will be moved to useful or unuseful position simultaneously with the elevation or lowering of the window sash.
- 10 Another important object of the invention is to provide a window awning which can be easily controlled from the inside of the house.

Still another important object of the invention is to provide an awning which can be quickly mounted and with equal quickness demounted.

These and various other important objects and advantages of the invention will become apparent to the reader of the following specification.

In the drawings:—

20 Figure 1 represents a vertical sectional view through the improved awning and the window frame and sashes with which it is associated.

Fig. 2 represents an outside elevational view of the awning in useful position.

25 Fig. 3 represents a sectional view taken substantially on line 3—3 of Fig. 1.

Fig. 4 represents a perspective view of the awning frame.

30 Fig. 5 represents an enlarged fragmentary detailed sectional view taken substantially on line 5—5 of Fig. 2.

Fig. 6 represents an enlarged fragmentary detailed sectional view taken substantially on line 6—6 of Fig. 1.

35 Fig. 7 represents a fragmentary enlarged detailed sectional view taken substantially on line 7—7 of Fig. 3.

Referring to the drawings wherein like numerals designate like parts it can be seen that numeral 5 represents a conventional rectangular-shaped window frame in which the outer and inner sashes 6 and 7 respectively operate.

The upper rail of the frame 5 has a bore 8 extending therethrough and a bushing 9 is provided in each end of the bore 8 to afford a bearing 9 for the control strand 10.

40 The awning proper is denoted generally by numeral 11 and consists of the top portion *a*, the side portions *b*, and the depending apron portion *c* depending from the lower end of the portion *a*, as well as the side portions *b*. The upper portion of the top *a* is sewed to provide a hem *d* through which the rod 12 extends. A strip 13 is secured at its longitudinal edges to the lower 45 end of the top portion *a* so as to provide a pocket

through which the bight portion *e* of the U-shaped frame generally referred to by numeral 14 extends.

A tab 15 secured to the lower portion of the top section *a* with the strip 13 is fastened to the ring 16. This ring also has the lower external end of the strand 10 secured thereto as at 17 and this strand, at this end portion, extends through the eye 18 at the lower end of the top portion *a*.

The leg portions *g* of the frame 14 extend through the pockets 19 at the lower ends of the side walls *b*. Obviously, the frame 14 is of tensional material so that in assembling and mounting the awning, the pintle-like ends *h* of the frame 14 can be easily engaged into the sockets 20 on the frame 5.

On each side portion of the frame 5 adjacent its upper end is provided a cup-like socket 21, one of which is provided with a slotted top portion 22. In mounting the upper portion of the awning, one end of the rod 12 is inserted into the socket 21 at the left being brought into Fig. 3, while the opposite end of the rod 12 is lowered down through the slot 22 in the remaining socket 21 for rest in the socket 21 last mentioned.

An eye 23 can be provided on the top portion of the top *a* for guiding the strand 10, and facilitates folding of the awning when in the folded position shown in dotted lines shown in Fig. 1.

As is clearly shown in Fig. 1, the inner end of the strand 10 is provided with a ring 24 which engages over the hook 25 on the lower portion of the inner sash 7. The strand 10 is just of sufficient length as to permit the awning 11 to assume the full useful position shown in Fig. 1 when the sash 7 is in the completely open position shown in Fig. 1. Of course, the ring 24 can be detached from the hook 25 to permit the awning to be operated independently of the sash 7.

Furthermore, the strand 10 can be of any desired length so that the awning may assume a fully useful position at any predetermined position of the sash 7. Therefore, the important feature involved is the automatic means whereby the awning is controlled by the sash; the means whereby the awning can be detached from the sash, and the means whereby the awning proper can be quickly mounted and demounted with respect to a window frame.

While the foregoing specification sets forth the invention in specific terms, it is to be understood that numerous changes in the shape, size and materials may be resorted to without de-

parting from the spirit and scope of the invention as claimed hereinafter.

Having thus described my invention, what I claim as new is:—

- 5 1. In combination, a window frame, a swingable awning mounted on the frame, said frame being provided with a transversely extending bore in the upper portion thereof, and a strand connected to said awning and extending through 10 said bore to terminate on the inside of the frame, a slideable sash in the frame, said strand being secured to said sash whereby lowering or raising of said sash will result in the simultaneous raising or lowering of said awning.

2. In combination, a frame, a swingable awning mounted in the frame, said frame being provided with a transversely extending bore in the upper portion thereof, a strand extending from the lower portion of the awning at the outer part thereof through said bore to terminate on the inside of the frame, a swingable sash in the frame, said strand being secured to the said sash at the lower portion thereof, whereby lowering or raising of said sash will result in the simultaneous raising or lowering of said awning.

GEORGE H. FOERSTER.
